UNITED STATES PATENT OFFICE.

HERMANN SCHARF, OF HALLE-ON-THE-SAALE, GERMANY.

SAFETY-BELT.

SPECIFICATION forming part of Letters Patent No. 530,799, dated December 11, 1894.

Application filed June 30, 1894. Serial No. 516,208. (No model.)

To all whom it may concern:

Be it known that I, HERMANN SCHARF, asse-
cuzanz-inspector, of 20 Geiststrasse, Halle-on-
the-Saale, Germany, have invented a Safety-
5 Belt, of which the following is a specification,
reference being had therein to the accompany-
ing drawings.

This invention is intended to prevent chil-
dren from falling out of their beds or per-
10 ambulators, and also to save people from a
fall in cleaning windows.

In the accompanying drawings: Figure 1
shows the belt arranged to prevent children
from falling out of their beds or perambu-
15 lators. Fig. 2 shows the belt arranged to save
people from a fall in cleaning windows.

The belt consists of a broad band *a*, to the
ends of which two narrow ribbons *b* *b'* are
fastened. Between one of these ribbons and
20 the central band *a*, a ring *c* is introduced,
through which the end of the other ribbon
can be drawn. The two ribbons *b* *b'* have at
the ends a number of holes by means of
25 which they can be attached to the outside of
perambulators, beds or window sills, the cen-
tral band *a* being put around the body of the
person who is to be protected from a fall.

If a child is to be protected against falling,
when in its perambulator or bed, the central
30 band *a* is put round the back of the child,
the ring *c* resting in front of the body, and
the two ends of the ribbons *b* *b'* are fastened
to the perambulator or to the bed. In case
35 a person is to be protected against a fall from
windows, the broad central piece *a* is put
round the body in such way that the ring *c*
rests on the back and the ends of the ribbons
are attached to the sides of the window sill.

In order to prevent, in the first arrangement,
40 the tightening of the belt round the child's

body, through its movements a pin *d* is passed
under the ring *c* through one of the holes in
the ribbon *b* which has been drawn through
the ring. Thus the belt surrounds the child
but loosely, giving it full liberty to move 45
about.

When the child bends over the bed or per-
ambulator, exposing itself to the danger of
falling over, its body still remains in a re-
clining position, through leaning on one side 50
of the broad band *a*, and this protects the
child, making a fall as impossible as it is to
twist the body out of the belt. Such a twist-
ing out of the body could however, easily occur
if a person fell from a window, and therefore 55
the belt ought to tighten itself round the
body in case of such a fall. For this reason
the pin *d* must then be passed over the ring
c as shown in Fig. 2.

The pin *d* is fastened to the belt with a rib- 60
bon *e*, and can be kept, when not required, in
a sheath *f* which is attached to the belt.

What I claim, and desire to secure by Let-
ters Patent of the United States, is—

The safety belt provided with an attaching 65
device on each end, a ring some distance from
one end through which the other end of the
belt is to be passed, and a pin to pass through
said inserted end and abut against said ring
while leaving said end to work freely in one 70
direction through said ring, substantially as
described.

In testimony whereof I have signed my
name to this specification in the presence of
two subscribing witnesses.

HERMANN SCHARF.
